Primary Examiner — Ralf Seifert(74) *Attorney, Agent, or Firm* — Li & Cai Intellectual Property (USA) Office(57) **CLAIM**

The ornamental design for an “elastic element,” as shown and described.

DESCRIPTION

FIG. 1 is a perspective view of an elastic element showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle thereof; and,

FIG. 9 is a referential view showing my new design as it would appear when in use.

The broken line showing of a slider in FIG. 9 is included for the purpose of illustrating environmental matter and forms no part of the claimed design.
